PLUG SWITCH

Filed April 6, 1928

UNITED STATES PATENT OFFICE

MAX TISCHLER, OF NEWARK, NEW JERSEY, ASSIGNOR TO REFLEX ENGINEERING CORPORATION, OF NEWARK, NEW JERSEY, A CORPORATION OF NEW JERSEY

PLUG SWITCH

Application filed April 6, 1928. Serial No. 267,844.

This invention relates to multiple parallel circuit couplings, and especially to devices of the block type wherein two pairs of stranded conductors, each pair being respectively positive and negative, are operatively engageable with mating conductors in a similar block, such structure being commercially known as four contact attachment plugs, as used on vitaphone outfits, etc., etc.

Although devices for like purposes are well known, their construction is often such as to be unwieldy, heavy, prone to accidental separation and may transmit current to the hand of an operator in maneuvering the same.

Having these matters in mind, it is one of the objects of the present invention to provide an electrical coupling of the type described that is compact, light in weight and easily handled by a novice without danger of receiving current or the possibility of creating a short circuit at any of the terminals.

A further feature is in the provision of means whereby each terminal contact is completely embedded in a block of dielectric material, provision being made for positively anchoring each terminal and for conducting current to the anchorage elements.

Another aim is to provide a spring clip for each terminal having a tendency to draw the mating parts into intimate relation and resisting separation except upon the application of considerable force.

These and other advantageous objects are accomplished by the novel construction and arrangement of parts as hereinafter described, and illustrated in the accompanying drawings, constituting an important portion of this disclosure, and in which:

Figure 1 is a plan view of an embodiment of the invention, showing the parts in operative position, the anchorage cover plates being omitted.

Figure 2 is a side elevational view of the same.

Figure 3 is a view similar to Figure 1, but showing the blocks separated.

Figure 4 is a view similar to Figure 2 with the blocks spaced apart as in Figure 3.

Figure 5 is an end view of the block shown in the left hand portion of Figure 4.

Figure 6 is an enlarged longitudinal sectional view of the two blocks with one of the paired terminal contacts as anchored there-in.

Figure 7 is a plan view of a pair of the contacts spaced apart.

Figure 8 is a transverse sectional view of the contacts as in engagement and held by a spring clip.

The device is composed primarily of two equal rectangular blocks 15 and 16 having smooth outer faces adapted to abut when in operative position. The rear portions 17 and 18 of the blocks are reduced in thickness at the top and bottoms and are tight fitted between flanges 19 extending from metal caps 20, aluminum being preferred, these caps having extending hubs 21 provided with clamps 22 to hold the entered cables 23—23'—24—24' in place.

The clamps 22 are provided with binding screws 25, and the caps are held to the block elements 17—18 by screws 26, as entities.

It is preferred in practice to form the blocks in two sections, the same being firmly held together by screws 27 passing through their forward portions and pairs of screws 28 through the rear portions.

These rear portions 17—18 contain transverse recesses 29—30, joined at the center by longitudinal recesses 31—32 which register with openings in the hubs 21 to admit entrance of the cables which are stranded, as at 23^a, 23^b, 24^a, and 24^b and their ends held in electrical engagement with screws 33—34 and 35—36 set in the recesses 29 and 30 respectively.

A circular opening 37 is formed in the face of the block 15 and a corresponding pin 38 is fixed to extend from the face of the block 16, acting as a dowel in causing registration of the blocks 15 and 16.

Each of these blocks contains circular openings 40—41 which extend into the recesses 29—30, and which are covered by insulating plates 42—43, the same being level with the forward portion of the blocks 15—16, as best seen in Figure 6, these plates being held in

position by screws engaging in openings 44.

Tightly fitted to each opening 41 is a metal plug 45 containing an axial opening 46 with which intersects a transverse recess 47. The inreaching end of the plug is flattened on the upper side, as at 48, and drilled to receive a clamp screw 34, which, as has been noted, is in electrical engagement with one of the branches or strands of a conductor, thus constituting a firm and efficient anchorage.

10 Set in a longitudinal slot in the upper side of the plug is a spring arm 49 secured in any preferred manner near its innermost end, the opposite end being down bent to produce a 15 detent 50, reaching into the recess 47 and slightly into the bore 46.

10 In the opening 40 is set a similar plug 51 having a flattened extension 52 at its inner end held by the screw 36. At the front end of 20 the plunger is a projection 53 suited to neatly fit the opening 46 and provided with an annular recess 54, registrable with the recess 47, to receive the detent 50 which is arranged to 25 make contact preferably with the front edge of the recess, thus drawing the plugs towards each other and preventing separation unless considerable force be used.

While certain preferred embodiments of 30 this device have been shown and described, it will be understood that changes in the form, arrangements, proportions, sizes and details thereof may be made without departing from the scope of the invention as defined in the appended claim.

35 Having thus described the invention, what is claimed as new and desired to secure by Letters Patent, is:—

40 A plug switch, comprising a pair of blocks of dielectric material, each block having a transverse recess and a pair of axial passages communicating therewith, metal sockets fitted in the axial passages of one of the blocks, each of said sockets having an axial recess, means for securing the sockets to the block, a flat 45 spring detent secured to each socket, said detents projecting into the axial recesses of the sockets, cylindrical plugs carried in the axial passages of the other block, each of said plugs having a reduced portion adapted to be received in an axial recess of the socket, each of the reduced portions of the plugs having a circumferential recess adapted to cooperate 50 with a detent to hold the two blocks together, said first block having a recess in its face, a 55 guide pin on the second block adapted to enter the recess to assist in holding the blocks in a predetermined position, and metal caps partially surrounding the dielectric blocks.

60 This specification signed this thirty-first day of March, 1928.

MAX TISCHLER.
